James W. Bergen, Lewisburg, Pa., and Joseph T. Kas-przycki, St. Charles, Mo., assignors to ACF Industries, Incorporated, New York, N.Y., a corporation of New Jersey

Filed May 26, 1965, Ser. No. 85,457

Term of patent 14 years

(Cl. D66—1)

FIG. 2.

FIG. 3.

FIG. 4.

FIGURE 1 is a perspective view of a railway car showing our new design;

FIGURE 2 is a perspective view of one end of the railway car shown in FIGURE 1;

FIGURE 3 is a perspective view of the other end of the railway car shown in FIGURE 1; and

FIGURE 4 is a top plan of the railway car shown in FIGURES 1-3.

The side of the railway car not shown in the drawings, is substantially the same as that shown.

The dominant features of the design reside in the shape and appearance of the railway car shown in full lines.

We claim:

The ornamental design for a railway car, as shown and described.
